FIG-1.

FIG-3.

JARRETT B. WOOD.
INVENTOR.

BY Charles P. Burke

ATTORNEYS.

UNITED STATES PATENT OFFICE

2,021,823

STEAM BOILER

Jarrett B. Wood, Tulsa, Okla.

Application February 19, 1934, Serial No. 711,920

4 Claims. (Cl. 122—467)

My invention consists in new and useful improvements in steam boilers and is in the nature of an improvement of the boiler described in United States Letters Patent No. 1,819,350 granted to me on August 18, 1931.

The primary object of the present invention is to provide a steam boiler which is compact in construction and of high efficiency in proportion to its size, the various elements of the assembly being so arranged with relation to the fire-box as to facilitate a maximum utilization of the heat units generated in the fire-box.

Another object of my invention is to provide a structure wherein a portion of the steam generated is subjected to superheating, means being provided for regulating the temperature of the superheated steam as it leaves the boiler for utilization.

A further object of my invention resides in the provision of a combination water leg and fire-box which greatly increases the efficiency of the boiler assembly.

A still further object of my invention is to provide means for the maintenance of a quantity of reserve steam in the event of a sudden heavy steam demand, and to further maintain a constant water endurance level.

Still another object of my invention resides in my improved arrangement for providing a maximum circulation of water in the boiler.

With the above and other objects in view which will appear as the description proceeds, my invention consists in the novel features herein set forth, illustrated in the accompanying drawing and more particularly pointed out in the appended claims.

Referring to the drawing in which numerals of like character designate similar parts throughout the several views,

Fig. 1 is a vertical sectional view of my improved boiler taken on line A—A of Fig. 2.

Fig. 2 is a transverse sectional view taken on line B—B of Fig. 1, and

Fig. 3 is a sectional view showing a modified form of heat exchanger for regulating the temperature of the superheated steam.

In the drawing, 1 represents a lower head which is substantially cylindrical in shape and terminates at its lower extremity in an annular water leg 2 which houses a fire-box 3, the latter being provided with any suitable burner (not shown). A vertically extending centrally disposed column 4 connects the upper extremity of the head 1 with the lower extremity of an upper head 5, the lat-

ter being also substantially cylindrical in shape and disposed coaxially above the lower head.

The boiler assembly is enclosed in a jacket 27 embracing the peripheral walls of the heads 1 and 5 and provided at its upper extremity with a removable cover 28 suitably flanged for engagement with the upper end of the jacket 27.

In the annular space 8 formed by the walls of the column 4 and jacket 27 between the lower head 1 and upper head 5, I provide two series of alternately disposed steam superheating coils 6 and water circulating coils 7. Referring to Fig. 1, it will be noted that for convenience I have shown one superheating coil and one water coil on opposite sides of the figure.

As also shown in Fig. 1, the upper ends of the superheating coils 6 are open and extend above a predetermined water level maintained in the head 5, the lower ends of said coils terminating in communication with an annular header 9 which is located in the lower portion of the space 8 and discharges at one side of the boiler into an outlet pipe 10 from which steam may be led to an engine or other point of service.

The alternately arranged water coils 7 open at their upper extremities into the lower portion of the upper header 5 and terminate at their lower extremities in communication with the upper portion of the lower header 1, whereby the water heated in the boiler is circulated through the system.

A series of short flues 11 extending vertically through the header 1 connect the fire-box 3 with the annular chamber 8 whereby the hot flue gases are conducted to the space surrounding the coils 6 and 7. A second series of short flues 12 extend vertically through the upper header 5 and connect the upper end of the chamber 8 with a smoke chamber 13 in the upper portion of the jacket 27, the spent gases and smoke escaping through a suitable opening in the top of the cover 28.

29 represents a series of longer flues which are arranged substantially centrally of the assembly, lying within the confines of the column 4 and extending vertically through the lower and upper heads 1 and 5, respectively, said flues placing the upper portion of the fire-box 3 in communication with the smoke chamber 13 and conducting hot flue gases through the column 4.

The upper head 5 is preferably provided with a perforated baffle 14 extending transversely across the head and located at a point above the water level maintained in said head. This baffle is for the purpose of aiding in drying the steam

before it enters the superheating coils 6 which, it will be noted, terminate above the baffle.

In the smoke chamber 13, I provide a reserve steam drum 16 opening at its lower end in communication with the central portion of the head 5 above the baffle 14 through the medium of a vertical conduit 17. A pipe 18 leads from the drum 16 and extends to the exterior and down the side of the boiler where it is joined by a pipe 15 leading from the upper head 5. A valve V¹ is preferably provided in the line 18 between its connection to the drum 16 and the junction of line 15, whereby steam may be withdrawn from either the upper head 5, or both the upper head and the drum as desired.

The pipe 18 terminates at its lower end in a T-connection 30 which extends in one direction to a coil 19 located in a water chamber 22, said coil being connected at its discharge end by means of a T 31 to a pipe 32 which leads to the steam discharge pipe 10. A by-pass pipe 20 connects the pipe 18 with the pipe 32 whereby through the manipulation of valves V², V³ and V⁴, the steam from pipe 18 may be passed through the coil 19 to pipe 32 and discharge pipe 10, or it may be by-passed through pipe 20 directly to pipe 32 and discharge pipe 10.

The water chamber enclosing the coil 19 is provided at its upper end with an inlet connection 23 and at its lower end with a discharge connection 25 which leads to the inlet pipe 24 of the lower head 1. Thus the stream of water being fed from any suitable source through water inlet pipe 24 into the lower head 1 may, if desired, be augmented and preheated by the admission of water from chamber 22 through pipe 25.

Referring to Fig. 3 which shows a modified form of heat exchange element, it will be seen that instead of the arrangement shown and described in connection with Fig. 1, the steam discharge pipe 10' is directly connected with the inlet end of the coil 19' by the pipe 20', and the discharge end of said coil is connected back into the steam discharge pipe by means of pipe 21', valves V⁵, V⁶ and V⁷ being provided for controlling the flow as hereinafter described.

Having thus described the construction and assembly of my improved steam boiler, its operation is as follows:

Water is charged to the lower head 1 through pipe 24, rising through the central column 4 to a predetermined level in head 5. As before stated, this charging water may be preheated by the admission of heated water from the chamber 22 of the heat exchanger. The heat from the fire-box 3 and the hot flue gases passing upwardly through the flues 11, 29 and 12 bring about a sufficiently high temperature in the boiler to cause the formation of steam, the greater portion of which is generated in the column 4, the water coils 7 providing for the circulation of heated water in the boiler. The generated steam rises to the upper head 5 where it comes in contact with the baffle 14 which aids in drying the steam before it enters the upper ends of the steam coils 6. These coils conduct the steam downwardly through the annular chamber 8 where it is superheated by the flue gases entering said chamber through flues 11, the superheated steam being discharged into a common header 9 and from thence to any point of use through discharge line 10.

In order to regulate the temperature of the steam flowing through pipe 10 to the point of

use, I may mix with the superheated steam leaving the header 9 suitable quantities of unsuperheated steam direct from the upper head 5 through pipes 15 and 18, and with the apparatus shown in Fig. 1, this regulation may be carried out in two ways. First, by closing valves V² and V³ and opening valve V⁴, the unsuperheated steam may be conducted through pipes 15, 18, 20 and 32 directly into the discharge line 10. Secondly, by opening valves V² and V³ and closing valve V⁴, the steam from the upper head 5 may be conducted through pipes 15 and 18, through the coil 19 in water chamber 22 and then through pipe 32 into the steam discharge pipe 10.

I may also, when desired, instead of carrying out either of the foregoing operations for the regulation of the temperature of the steam and for the further purpose of supplying an additional quantity of steam, inject water through pipe 26 into the stream of superheated steam leaving the header 9 through pipe 10.

The steam drum 16 located in the upper portion of the boiler is used for the purpose of providing a large steam liberating space or the maintenance of a larger amount of steam in reserve in the event of a sudden heavy steam demand. Furthermore, this arrangement provides a more constant steady flow of steam to the steam header 9 in case of sudden heavy demands and tends to maintain a constant water endurance level.

By manipulating the valve V¹, a portion of the reserve steam in drum 16 may be withdrawn through pipe 18 for use in regulating the temperature of the steam discharged through pipe 10 in either of the manners hereinbefore described.

The operation of the modified form of heat exchanger shown in Fig. 3 is as follows, it being understood that otherwise the structure of the boiler itself is the same as that shown in Fig. 1.

By opening valves V⁵ and V⁷ and closing valve V⁶, the unsuperheated steam from line 18 may be conveyed directly through pipe 20' into the discharge pipe 10' for regulating the temperature of the discharged steam. On the other hand, by closing valves V⁷ and V⁸ and opening valves V⁵ and V⁶, the superheated steam leaving the header 9 may be conducted from pipe 10' up through pipe 20' and passed through the coil 19' in the water chamber 22' where its temperature is reduced to the desired extent, and back through pipe 21' into the discharge pipe 10'. Furthermore, by closing valve V⁸ and opening valves V⁵ and V⁶ and throttling valve V⁷, I may split the stream of superheated steam leaving the header through pipe 10' so that a portion thereof will pass through pipe 20' and coil 19' and the remainder continue through pipe 10'.

It will thus be seen that I have provided a highly efficient steam boiler which is capable of producing any desired quantity or quality of steam for use in connection with any steam operated apparatus.

From the foregoing it is believed that my invention may be readily understood by those skilled in the art without further description, it being borne in mind that numerous changes may be made in the details of construction and operation without departing from the spirit of the invention as set out in the following claims.

What I claim and desire to secure by Letters Patent is:

1. A steam boiler including a fire-box, a water

head immediately above said fire-box, a water and steam head spaced above said first named head, a centrally disposed column connecting said heads and forming the inner wall of an 5 annular heating chamber, said column placing said heads in communication, a smoke chamber above said upper head, a series of flues extending from said fire-box through said heads and column to said smoke chamber, a series of water 10 circulating coils located in said heating chamber and placing the water space of said upper head in communication with said lower head, a series of steam superheating coils located in said heating chamber, said superheating coils being open at 15 one end to the steam space of said upper head, their lower ends terminating in a common header, flues leading from said fire-box to the lower end of said heating chamber through said water head, flues leading from said heating chamber to said 20 smoke chamber through said steam and water head, and a conduit for conducting steam from said header to a point of use.

2. A steam boiler including a fire-box, a water head immediately above said fire-box, a water and steam head spaced above said first named head, a centrally disposed column connecting said 25 heads and forming the inner wall of an annular heating chamber, said column placing said heads in communication, a smoke chamber above said upper head, a series of flues extending from said 30 fire-box through said heads and column to said smoke chamber, a series of water circulating coils located in said heating chamber and placing the water space of said upper head in communication with said lower head, a series of steam 35 superheating coils located in said heating chamber and alternately spaced with respect to said water coils, said superheating coils being open at one end to the steam space of said upper head, 40 their lower ends terminating in a common header, flues leading from said fire-box to the lower end of said heating chamber through said water head, flues leading from said heating chamber to said smoke chamber through said steam and water 45 head, and a conduit for conducting steam from said header to a point of use.

3. A steam boiler including a fire-box, a water head immediately above said fire-box, a water and steam head spaced above said first named head, 50 a centrally disposed column connecting said heads and forming the inner wall of an annular heat-

ing chamber, said column placing said heads in communication, a smoke chamber above said upper head, a series of flues extending from said fire-box through said heads and column to said smoke chamber, a perforated baffle located in said upper head above the water level, a series of water 10 circulating coils located in said heating chamber and placing the water space of said upper head in communication with said lower head, a series of steam superheating coils located in said heating chamber and alternately spaced with respect to said water coils, said superheating coils being open at one end to the steam space of said upper head above said baffle, their lower ends terminating in a common header, flues leading from said 15 fire-box to the lower end of said heating chamber through said water head, flues leading from said heating chamber to said smoke chamber through said steam and water head, and a conduit for conducting steam from said header to a point of use.

4. A steam boiler including a fire-box, a water head immediately above said fire-box, a water and steam head spaced above said first named head, a centrally disposed column connecting said 25 heads and forming the inner wall of an annular heating chamber, said column placing said heads in communication, a smoke chamber above said upper head, a series of flues extending from said 30 fire-box through said heads and column to said smoke chamber, a perforated baffle located in said upper head above the water level, a series of water circulating coils located in said heating chamber and placing the water space of said 35 upper head in communication with said lower head, a series of steam superheating coils located in said heating chamber and alternately spaced with respect to said water coils, said superheating coils being open at one end to the steam space of said upper head above said baffle, their lower 40 ends terminating in a common header, flues leading from said fire-box to the lower end of said heating chamber through said water head, flues leading from said heating chamber to said smoke chamber through said steam and water head, a 45 conduit for conducting steam from said header to a point of use, and a reserve steam drum located in said smoke chamber and in communication with the steam space of said upper head.

JARRETT B. WOOD.
